WEAK BOTTLE ELIMINATOR

Truman L. Blanton, Ventura, Calif.

Application October 10, 1951, Serial No. 250,751

2 Claims. (Cl. 73—37)

1

This invention relates to bottle washing machines particularly of the type used for washing soft drink and beer bottles, and in particular an attachment for a bottle washing machine whereby pressure is applied to the interiors of the bottles so that weak bottles are exploded or broken before they reach the filling operation or machine.

The purpose of this invention is to provide means for eliminating weak bottles used for soft drinks and the like wherein the bottles are eliminated in the washing machine or step and before they reach the filling machine or operation.

In the conventional method of filling soft drink bottles, particularly where carbonated water is used the bottles are subjected to internal pressure, such as fifty pounds, and when a weak bottle explodes the material is not only lost but there is danger of the fine glass working into adjoining bottles. Furthermore bottles of this type often break in transit and when on display in a store or the like. In such instances cleaning up the broken bottles requires considerable time and there is danger of injury to the attendant and also to customers. With this thought in mind this invention contemplates a method of exploding weak bottles before they reach the filling stage by providing an attachment in a bottle washing machine whereby pressure is applied to the bottles in the washing machine, and with the pressure fifteen to twenty pounds greater than the pressure to which the bottles are subjected in filling, bottles that will not withstand pressure are broken or exploded and thereby eliminated in the washing machine.

With the bottles broken in the washing machine it is not essential to stop the operation of the machine as provisions may be made to take care of the broken glass and the operator has an opportunity to replace the broken bottle before the bottles reach the filling stage.

The object of this invention is, therefore, to provide an attachment for bottle washing machines whereby bottles are subjected to a pressure greater than that normally required of the bottles before the bottles reach the filling stage.

Another object of the invention is to provide a bottle testing attachment for bottle washing machines that is adapted to be actuated by a moving part of the machine.

Another object of the invention is to provide a bottle testing attachment for bottle washing machines wherein either air or water under pressure may be applied to the bottles.

A further object of the invention is to provide

2

a bottle testing attachment for bottle washing machines which is of a simple and economical construction.

With these and other objects and advantages in view the invention embodies an attachment having a traveling beam with a plurality of pressure cups carried by the beam and positioned to engage the ends of bottles in a bottle carrier of a bottle washing machine and means for actuating the beam by a moving part of the machine and also means for supplying air or water under pressure through the pressure cups at the time the cups are positioned over the ends of the bottles.

Other features and advantages of the invention will appear from the following description taken in connection with the drawings wherein:

Figure 1 is an elevational view showing part of a bottle washing machine in which bottles are placed into a bottle carrying conveyor and in which parts are broken away illustrating the bottle testing attachment of this invention.

Figure 2 is a sectional plan through the part of the machine as shown in Figure 1 taken on line 2—2 of Figure 1.

Figure 3 is a vertical section similar to the elevational view of Figure 1 showing the attachment in the position of applying pressure to a bottle.

Figure 4 is a detail showing a view similar to that shown in Figure 3 with the pressure cup shown in elevation and with a crank arm on the near end of the machine omitted.

Figure 5 is a detail showing one end of the traveling beam with the pin extended from the end of the beam extended through a slide block positioned between the slide rails, the said slide block and rails being shown in section.

Figure 6 is a section taken on line 6—6 of Figure 5 showing the slide rails in elevation and the beam in section.

Figure 7 is a sectional plan taken on line 7—7 of Figure 6 also showing the slide block in section and positioned to travel between the slide rails.

Figure 8 is a detail showing the longitudinal section through one of the pressure cups, illustrating the method of sealing the cup over the end of a bottle.

Figure 9 is a longitudinal section through the valve by which fluid under pressure is admitted to the pressure cups.

Figure 10 is a similar view showing the valve in the open position.

Referring now to the drawings wherein like reference characters denote corresponding parts, the improved bottle testing attachment of this invention includes a plurality of pressure cups 10

carried by tubular stems 11 which are supported in a traveling beam 12, slide blocks 13 and 14 in which the ends of the beam 12 are mounted and which are positioned to slide between slide rails 15 and 16 at one end and 17 and 18 at the other, a link 19 by which the attachment is actuated with a bell crank 20 of the machine and a valve 21 with which fluid under pressure is supplied to the pressure cups at the time the ends of bottles are sealed in the cups.

The pressure cups 10 are formed, particularly as illustrated in Figure 8, wherein the tubular stems 11 are threaded in one end of the cups. The opposite ends of the cups are flared outwardly forming a guide flange 23 by which bottle necks 24 are centered in the cups with the openings of the bottle necks positioned to register with openings 25 in gaskets 26 that are positioned against seats 27 in the intermediate parts of the cups. The gasket or washer 26 is provided with a sealing flange 28 that fits snugly over the end of a bottle thereby providing a pressure seal.

The traveling beam 12 is substantially channel shape in cross section and the stems 11 extend through the beam, being secured in position by collars 29 which are positioned against the outer surface of a plate 30 mounted on the edges of the flanges of the beam.

The outer ends of the stems 11 are connected to flexible tubes 31 by coupling members 32 and the tubes 31 are connected to nipples 33 of a header 34 by coupling members 35. The header 34 is connected to the valve 21 by a tube 36 which is secured in a socket 37 of the valve 21 and the opposite side of the valve is supplied with fluid under pressure through the tube 38 that is connected in a socket 39.

The valve 21 is provided with a bushing 40 which is secured in the end of the valve by bolts 41 that extend through a flange 42. The bushing 40 is provided with a valve seat 43 and an opening 44 in the center of the bushing is positioned to communicate with side outlets 45, one of which is positioned to communicate with a socket 37 from which the tube 36 extends.

The valve 21 is provided with a valve stem 46 on which the valve member 47 is positioned and, as shown in Figures 9 and 10 the valve stem extends through a spring chamber 48 in which the spring 49 is positioned. The spring bears against a closure member 50 in the outer end of the casing 48 and the washer 51 on the stem 46 whereby the valve member is held in the closed position. The spring casing 48 is provided with a threaded tubular neck 52 that is threaded into a socket 53 in the end of the valve 21.

The traveling beam 12 is provided with pins 54 and 55 which extend through the slide blocks 13 and 14, as illustrated in Figure 5, and on the outer ends of which crank arms 56 and 57 with elongated slots 60 therein are positioned. The pins 54 and 55 are provided with sealing washers 61 and the slide bars are provided with flanges 62, the flanges being positioned against the ends of the traveling beam.

The slide blocks are positioned to slide between the slide rails 15 and 16 in one end, and 17 and 18 at the other and the slide rails 15 and 16 are provided with stop blocks 63 and 64. The slide rails 17 and 18 are provided with similar stop blocks as indicated by the numerals 65 and 66.

The slide rails 15 and 16 are attached to a plate 67 of a bottle washing machine with an angle support 68 and the slide rails 17 and 18 are attached to the same plate by an angle sup-

port 69. The opposite ends of the slide rails are supported by angle iron struts 70 which are carried by supports 71.

The crank arms 56 and 57 are mounted on a shaft 72 which is journaled in bearings 73 and 74 on end plates 75 and 76 of the bottle washing machine and the extended end of the shaft is provided with an arm 77, the end of which is connected to the link 19 with a bolt 78. The opposite end of the link 19 is attached to the bell crank 20 which is pivotally mounted on a stub shaft 79 of the machine, by a bolt 80.

The link 19 is provided with threaded ends with nuts 81 and 82 thereon, whereby the ends of the link are secured in yokes 83 and 84, on the bolts 78 and 80.

The bell crank 20 is also connected to a rod 85 with a bolt 86 and the rod 85, which is adjustably mounted in sockets 87 and 88 is attached to a guide arm 89 on the actuating shaft 90 of the machine by a bolt 91. The extended end of the rod is provided with a spring 92, one end of which is positioned against the socket 88 and the other against a collar 93 whereby the rod 85 is resiliently urged upwardly.

The actuating shaft 90 of the machine is actuated by the machine to cause downward movement of the arm 89 which exerts force on the rod 85 to urge it downward against the action of the spring 92. This rod in turn moves bell crank 20 which draws the link 19 backward to move the travelling beam 12. Thus as the bottle washing machine operates to wash the bottles, the travelling beam is moved to force the cups 10 into engagement with the mouth of the bottles.

The extended end of the valve stem 46 is provided with a projection 94 and the projection is positioned to be engaged by the rod 85 whereby, as illustrated in Figure 3, the valve is opened as the rod 85 moves from the position shown in Figure 1 to that shown in Figure 3.

The cups 10 are resiliently held outwardly by springs 95 and as the traveling beam 12 is actuated from the position shown in Figure 1 to that shown in Figure 3 by the actuating shaft 90 of the machine the cups extend over the ends of bottles, indicated by the numeral 96, in the bottle carrier 97 whereby the sealing elements 26 and 28 fit snugly over the ends of the bottles providing a sealed connection.

The bottles are retained in position in the carrier by a beam 98, which is preferably T-shaped in cross section, and as the carrier travels upwardly with the bottles the spring guides 99, extended downwardly from the beam 98, urge the bottles toward the cups.

The bottles are placed in the bottle carrier 97 from a shelf 100 and the carrier travels on a track formed with angle irons 101 and 102 on which the carrier element is held by chains 103 and 104, respectively, the chains being provided with rollers 105 and 106.

With the parts arranged in this manner air, water, or other fluids may readily be applied to bottles of a bottle washing machine and as the pressure is applied to the interior of the bottles weak bottles will explode or break and the broken glass will drop downwardly through the machine without necessarily stopping the machine and without danger of broken glass from the bottles working into other bottles being washed in the machine.

It will be understood that modifications may be made in the design and arrangement of the

parts without departing from the spirit of the invention.

What is claimed is:

1. In a bottle washing machine attachment, the combination which comprises spaced pairs of parallel tracks mounted in a bottle washing machine, slide blocks slidably mounted in said tracks, a traveling beam positioned between the tracks and journaled in said slide blocks, spaced tubular stems mounted in said traveling beam, pressure cups carried by extended ends of the stems, bottle neck sealing gaskets positioned in said pressure cups, a bottle carrier mounted whereby bottles carried thereby are positioned so that necks thereof are aligned with the pressure cups, means holding bottles in position in said carrier, means actuating the traveling beam with the pressure cups extended therefrom whereby the pressure cups extend over ends of bottles positioned in the carrier, means for resiliently urging said pressure cups to extended position, means supplying fluid under pressure to said bottles through the pressure cups, and said pressure supplying means is actuated by the means actuating the travelling beams.

2. In a weak bottle eliminator for a bottle washing machine having a bottle carrier provided with means for holding bottles therein and an actuating shaft for moving bottles into position

to be washed the improvement comprising a pair of parallel rails mounted at each side of said machine, a slide block positioned to travel between said parallel rails at each side of the machine, a beam journaled at the ends in said slide blocks, a plurality of pressure cups mounted in said machine and positioned to receive the open ends of bottles mounted in said bottle carrier, an arm connected to the actuating shaft of the machine, a spring biased rod pivotally connected to said arm, a bell crank lever pivotally connected to said rod, a link pivotally connected to said bell crank lever, and a second arm connected to said link and to the said beam for moving said pressure cups into sealing relation with the open ends of the bottles, and means supplying fluid under pressure to said pressure cups for ejection into the open mouths of said bottles.
